UNITED STATES PATENT OFFICE.

PERCY I. ANSORGE, OF BROOKLYN, NEW YORK.

DESIGN FOR A LIGHTING-FIXTURE BRACKET.

Application filed October 27, 1926. Serial No. 19,493. Term of patent 7 years.

To all whom it may concern:

Be it known that I, PERCY I. ANSORGE, a citizen of the United States, residing at 319 St. Johns Place, in the county of Kings, borough of Brooklyn, city and State of New York, have invented a new, original, and ornamental Design for a Lighting-Fixture Bracket, of which the following is a specification, reference being had to the accompanying drawing, forming part thereof.

Figure 1 is a front elevational view of a lighting fixture bracket, showing my new

design; it is to be understood that the un-ornamented portion within the outline shown is ornamented in the same manner as the completed portion more fully shown.

Figure 2 shows a diagrammatic outline of the article illustrated in Fig. 1, devoid of ornamentation, for the purpose of illustrating contour only.

I claim:

The ornamental design for a lighting-fixture bracket substantially as shown.

PERCY I. ANSORGE.
